UNITED STATES PATENT OFFICE.

EDWIN E. MELLENTHIN, OF WAUKESHA, WISCONSIN.

TEMPERATURE CONTROL FOR RADIATORS.

1,389,771.

Specification of Letters Patent. Patented Sept. 6, 1921.

Application filed February 10, 1921. Serial No. 443,942.

To all whom it may concern:

Be it known that I, EDWIN E. MELLENTHIN, a citizen of the United States, and resident of Waukesha, in the county of Waukesha and State of Wisconsin, have invented certain new and useful Improvements in Temperature Control for Radiators; and I do hereby declare that the following is a full, clear, and exact description thereof.

10 My invention refers to temperature control for water jacketed engines, and it has for its object to provide a simple, economical and effective means for maintaining approximately a uniform temperature in the 15 water circulating system by causing a positive circulation of tempered air about the radiator parts, including the heads and water cells or channels, the air being controlled as to temperature by indirect heat from 20 exhaust gases of the engine to thus insure maximum efficiency in the engine under various climatic conditions, and to prevent freezing under certain conditions.

With the above and other minor objects in 25 view, the invention consists in certain peculiarities of construction and combination of parts, as are hereinafter set forth with reference to the accompanying drawings and subsequently claimed.

30 In the drawings,

Figure 1 represents a side elevation of a water jacketed engine and its associated radiator having attached thereto a temperature controlling mechanism embodying the 35 features of my invention.

Fig. 2 is an enlarged detail longitudinal sectional view of a radiator constructed in accordance with my invention.

40 Fig. 3 is an enlarged longitudinal sectional view through an air receiving drum embodying one of the features of my invention, a compartment of the drum being arranged to envelop a standard exhaust pipe which may lead to the muffler through a direct discharge, and

Fig. 4 is a front elevation of the air receiving drum showing its open end equipped with a suction fan.

Referring to Fig. 2 of the drawings, the 50 radiator is provided with a bottom head 1 and a top head 2, which heads are connected by tubes 3 that constitute water cells or channels. The upper and lower heads are incased in metallic jackets 4-4', which 55 jackets are connected by jacket tubes 3' that incase the water channels 3. These jacket

elements are separated from their associated parts, so as to form uninterrupted air spaces 5' about the heads and communicating air spaces 6 about the tube channels. The upper head is provided with an air vent 7, which communicates with the air spaces 5', as shown, and this vent may be in some instances provided with a cap (not shown), or other closure device, whereby the vent 60 can be closed in some cases, or restricted in others. The upper head is connected to the water jacket A of the engine casing by means of a pipe B, as best shown in Fig. 1. The radiator jacket members which form 65 an air space about the parts of said radiator are covered by a shell 9 or insulating material, such as asbestos or the like, so as to exclude as near as possible the influence of the atmosphere upon the water circulating 70 through the system or parts of the radiator.

The bottom head 1 is connected by an exteriorly insulated pipe 10 to the air intake end 11 of a heating drum, the drum being provided with a rear compartment 12, which 80 is arranged to incase a coiled section 13' of an engine exhaust pipe 13. The compartment 12 is closed at its rear end by a cap 14 through which the exhaust pipe extends, as best shown in Fig. 3. The hot air compartment 85 12 and the air receiving compartment 11 are separated by a slidably valve plate 15 which may be adjusted to vary the intake area that forms a communication between the compartments and when the valve plate is ad- 90 justed, it may be locked in any predetermined position by a set screw 15', which passes through a mouth of the valve guide as shown. The front end of the drum is provided with an inwardly tapered deflector hood 95 16, which hood incases a fan 17 that is secured to a shaft 18 journaled in the hub of a spider 19, which spider is secured to the drum shell.

In this exemplification of my invention, 100 the opposite end of the fan shaft 18 is journaled in a bearing 20, and is secured to the engine casing and this end of the shaft carries a pulley 21, which pulley is in belt connection with a second pulley 21', but is 105 mounted on the shaft of the standard radiator fan C. Obviously, the fan 17 can be driven at any desired speed and from any moving part of the engine other than that shown.

110 In operating the engine under low temperature conditions, it is desirable to main-

tain the water in a circulating system at a relative high temperature, and in this instance, the valve 15 is adjusted so as to increase the inlet opening from the air compartment to the heating compartment of the drum to a maximum. Under these conditions, the cold air drawn into the drum compartment 11 through the spider 19, by action of the same, will be forced back into the heating compartment 12 and confined therein in more or less compact volume, whereby the exhaust gases passing through the coil 13 will heat the air to a comparatively high temperature, and as the fan continues to force air backward into the drum, the heated air will be caused to travel through the pipe 10 and circulate about the lower head channels and upper head of the radiator, so as to exert a heating influence upon the water contained in said radiator to thus insure maintaining it at the desired temperature. The surplus air caused to travel over the radiator parts is discharged through the vent 7.

It follows that when the atmosphere conditions are at normal winter temperature, the valve 15 can be lowered so as to restrict the volume of air that may pass into the heating end 12 of the drum.

In summer seasons when the temperature is somewhat high, the valve 15 can be entirely closed and the air drawn into the first compartment of the drum 11 will be forced at normal temperature directly through the air circulating system about the parts of the radiator, to thus prevent the water from rising above normal to hold the temperature of the water as near as possible at a pre-

terminated degree. By controlling the air circulating system positively in the manner mentioned, obviously it would be understood that the efficiency of the engine is materially increased, and in cold weather the hot air, which is introduced about the jacketed radiator parts, will serve as a blanket to prevent the water in the circulating system from freezing quite a length of time, even though the engine were not running, bearing in mind that all of the radiator parts are insulated by a cover of non-conductive material.

I claim:

In a temperature controlling apparatus for water cooled engines having a spent gas exhaust pipe and a radiator provided with jacketed upper and lower heads connected by jacketed water channels, there being an air space between the jacketed parts and a vent for the air space; the combination of a drum having a heating compartment increasing a portion of the engine exhaust pipe and an open ended air intake end, a valve for regulating communication between the air intake end and the heating end of the drum, a motor driven fan mounted in the air receiving end of the drum, and a pipe in communication with the air intake end of said drum and air space about the radiator parts, whereby air from the drum at predetermined temperatures may be positively forced about the water circulating system of the radiator.

In testimony that I claim the foregoing I have hereunto set my hand at Milwaukee, in the county of Milwaukee and State of Wisconsin.

EDWIN E. MELLENTHIN.
